ONE-PIECE PAPER CONTAINER

Jesse Norden, Kew Gardens, N. Y.

Application April 19, 1950, Serial No. 156,827

4 Claims. (Cl. 229—16)

1

This invention comprehends an improvement in the one piece paper container constituting the subject matter of my Patent No. 2,468,306, dated April 26, 1949. The improvement is highlighted by the provision of novel means for re-inforcing the vertical and base corners of the container in such manner as to more effectively resist rough usage.

I achieve this result by bevelling the vertical corners of the container—rectangular in cross section—and thus providing surplus paper for the flaps which are folded around the upright sides of the container to present multiply vertical corners, as well as, a tab for re-inforcing the bases of the corners.

In the drawings:

Figure 1 is a perspective view of the sheet after it has been subjected to two double foldings at right angles to each other—the position of the flaps after subsequent flexing being shown by dotted lines;

Fig. 2 is a top plan showing the shape of the components after they have received a preliminary upward folding and the corners have been suitably bevelled;

Fig. 3 is an enlarged, fragmentary top plan of one of the corners with an adjacent flap;

Figs. 4 and 5 are enlarged detail views showing the base corner tab and the manner of tucking it between the flap and one corner, and

Fig. 6 is a side elevation of the complete container.

The preliminary steps in forming the container up to and including Fig. 4 of the drawings are precisely as described in my aforesaid patent—see specification, column 2, lines 32 through 55 and column 3, lines 1 through 19—and for the sake of clarity the same reference numerals are employed to indicate corresponding parts.

Instead of having only a single thickness of material at the junction of the vertical side walls 26 and the radial flaps 21, 22, 23 and 24, as illustrated in Figure 5 of my patent—a definite weakness—I bevel the corners longitudinally, see Figure 2, at 27, 28, 29 and 30. In this way, I gain surplus material over the sharp 90 degree angle corners which obtained in my previous disclosure, and when this additional material—virtually becoming part of the flaps—is trained about the vertical walls 26 it augments the plies to three, 31, 32 and 33, where there was only one before.

Obviously, in the operation of bevelling the longitudinal corners, the corners of the bottom 34 must be included, and this results in the formation of a small tab 35—best seen in Figs. 4 and 55 a

2

5—which is folded upon itself and tucked inwardly and upwardly between the base of the adjacent flap 24 and the bevelled corner 30. The same construction is employed with respect to the other three base corners.

All parts of the container are sealed together in any suitable manner.

With the longitudinal corners and base corners thus re-inforced, I have provided a container which makes for true multiply construction throughout, and which for conventional use is practically invulnerable.

I claim:

1. An open ended container substantially rectangular in cross section, constructed from a blank of paper or the like having pleats forming a multiply bottom from the central portion of the blank and multiply side walls formed from portions extending vertically and radially of the central portion and bevelled multiply corners, the free edges of the blank terminating substantially in a common plane at the open end of the container, and the plies of the bottom, side walls and corners being sealed together.

2. An open ended container substantially rectangular in cross section, constructed from a blank of paper or the like having pleats forming a multiply bottom from the central portion of the blank and multiply side walls formed from portions extending vertically and radially of the central portion, the free edges of the blank terminating substantially in a common plane at the open end of the container, the vertical corners of the container being bevelled and having a multiply thickness, and the plies of the bottom, side walls and corners being sealed together.

3. An open ended container substantially rectangular in cross section, constructed from a blank of paper or the like having pleats forming a multiply bottom from the central portion of the blank and multiply side walls formed from portions extending vertically and radially of the central portion, and multiply corners, the free edges of the blank terminating substantially in

45 a common plane at the open end of the container, the base of each corner, adjacent the bottom, being folded upon itself to present a tab which is inserted between said radially and vertically extending portions, and the plies of the bottom, side walls and corners, and the tab, being sealed together.

4. An open ended container substantially rectangular in cross section, constructed from a blank of paper or the like having pleats forming a multiply bottom from the central portion of

2,572,655

3

the blank and multiply side walls formed from portions extending vertically and radially of the central portion, the free edges of the blank terminating substantially in a common plane at the open end of the container, the vertical corners of the container being bevelled and having a multiply thickness, the base of each corner, adjacent the bottom, being folded upon itself to present a tab which is inserted between said radially and vertically extending portions, and the

plies of the bottom, side walls and corners, and the tab, being sealed together.

JESSE NORDEN.
